ELECTRICAL CONNECTOR HOUSING

Bruno Baumans, River Forest, Ill., assignor to Molex
Incorporated, Downers Grove, Ill.

Filed Apr. 1, 1971, Ser. No. 130,550

Term of patent 14 years

Int. Cl. D13—03

U.S. CL. D26—1

FIG. 1 is a perspective view of an electrical connector housing, showing my new design;

FIG. 2 is a side view thereof;

FIG. 3 is an end view as taken from the right end in FIG. 2;

FIG. 4 is a bottom plan view; and

FIG. 5 is an end view taken from the left end of FIG. 2. The side which is not shown in FIGS. 1 and 2 is the same as the side which is shown.

I claim:

The ornamental design for an electrical connector housing, as shown and described.
